MAGNETIC AMPLIFIER

Melville C. Creusere, China Lake, Calif., assignor to the United States of America as represented by the Secretary of the Navy

Application August 13, 1954, Serial No. 449,810

7 Claims. (Cl. 235—61)

(Granted under Title 35, U. S. Code (1952), sec. 266)

The invention described herein may be manufactured and used by or for the Government of the United States of America for governmental purposes without the payment of any royalties thereon or therefor.

This invention relates to magnetic amplifiers and particularly to a summing magnetic amplifier which is particularly useful as a component of analogue computers. Previously known summing magnetic amplifiers have required a plurality of control windings, one for each electrical input. In such summing amplifiers, errors in the number of turns of any of the control windings will reduce the accuracy of the summation, and since the total number of turns which can be wound on the cores of a magnetic amplifier are limited, the maximum number of turns in each control winding will vary inversely with the number of control windings. Further, the magnitude of the positive feed back required to obtain a given open loop gain also varies inversely as the number of turns in each control winding.

The summing magnetic amplifier constituting this invention uses a single control winding so that a small error in the number of turns of the control winding will not adversely affect the computing accuracy of the amplifier. Further, since there is only one control winding, it may have a large number of turns, larger than the number of turns of each control winding of a magnetic amplifier having a plurality of control windings. This in turn requires a positive feedback of fewer ampere turns for a given open loop gain as compared with previously known summing magnetic amplifiers. As a result of this construction, the open loop linearity and accuracy of the summing amplifier are increased.

It is, therefore, an object of this invention to provide an improved summing magnetic amplifier having a single control winding.

It is a further object of this invention to provide an improved magnetic amplifier for summing a plurality of input voltages.

It is a still further object of this invention to provide a magnetic amplifier which is capable of adding algebraically a plurality of input voltages.

It is a further object of this invention to provide a summing magnetic amplifier having a single control winding in which voltages are balanced across the control windings so that substantially no current flows through the control winding.

It is a further object of this invention to provide a magnetic amplifier capable of solving linear equations having coefficients other than one.

It is still another object of this invention to provide a magnetic amplifier having a very high input impedance and a low output impedance.

Other objects and many of the attendant advantages of this invention will be readily appreciated as the same become better understood by reference to the following detailed description when considered in connection with the accompanying drawings wherein:

2

Fig. 1 is a schematic diagram of the summing magnetic amplifier;

Fig. 2 is a schematic diagram of a modification of the summing magnetic amplifier, and

Fig. 3 is a schematic diagram of a second modification.

Referring now to Fig. 1 the output circuit 10 of the summing magnetic amplifier 12 is arranged in the form of a standard voltage doubler magnetic amplifier; although any high gain type of magnetic amplifier could be used. In a preferred example, alternating current at 115 volts 2400 cycles per second is provided by source 14. The use of such high frequency A. C. permits the size of the components of the magnetic amplifier to be minimized. Obviously other frequencies and voltages may be used if desired. The output current, i_o flows through positive feedback winding 16 and load resistor R_a . Positive feedback winding 16 increases the open loop gain of the amplifier, minimizes the output impedance, and increases the summing accuracy.

The direct current bias voltage, E_c , is applied across the bias winding 18 of the summing magnetic amplifier 12 through bias resistor R_c . The values of E_c and R_c are chosen to provide a constant bias current such that the output voltage E_o will be directly proportional to the input current, i_{in} , which flows through control winding 20. Because of the characteristics of magnetic amplifier 12, E_o will never equal 0, and the variation of E_o with respect to i_{in} will not be linear below a certain minimum value of E_o . The voltage E_o will be substantially equal to the voltage at point 22₁ because of the fact that the resistance of the positive feedback winding 16 is low as compared to other resistances in the circuit.

Substantially D. C. input voltages E_{a1} , E_{a2} . . . E_{an} are applied to input terminals 22_{a1}, 22_{a2} . . . 22_{an} of input circuit 24, respectively. Input voltages E_{b1} , E_{b2} . . . E_{bm} are applied to input terminal 22_{b1}, 22_{b2} . . . 22_{bm} of input circuit 26, respectively. Input voltages E_{a1} , E_{a2} . . . E_{an} are applied to control terminal 28 of control winding 20 through resistors R_{a1} , R_{a2} . . . R_{an} , respectively. Input voltages E_{b1} , E_{b2} . . . E_{bm} are applied to control terminal 30 of control winding 20 through input resistors R_{b1} , R_{b2} . . . R_{bm} , respectively.

For purposes of generalizing the theory of operation balancing resistor R_{ao} is connected between terminal 28 and ground and balancing resistor R_{bo} is connected between terminal 30 and ground. The summing process depends on the negative feedback of voltage E_{b1} , which is determined by the magnitude of the output current, i_o , through R_d , to control winding 20 so that:

$$i_{in} \approx 0 \quad (1)$$

where i_{in} is the current flowing through control winding 20. The feedback voltage E_{b1} is related to the output voltage E_o so that:

$$E_{b1} \approx E_o \quad (2)$$

Since the resistance of positive feedback winding 16 is very low, the sum of all the currents into control terminal 28 is:

$$\frac{E_{a1} - E_{x1}}{R_{a1}} + \frac{E_{a2} - E_{x1}}{R_{a2}} + \dots +$$

$$\frac{E_{an} - E_{x1}}{R_{an}} + \frac{0 - E_{x1}}{R_{ao}} - i_{in} = 0 \quad (3)$$

and the sum of all the currents into control terminal 30 is:

$$\frac{E_{b1}-E_{x2}}{R_{b1}} + \frac{E_{b2}-E_{x2}}{R_{b2}} + \dots + \frac{E_{bm}-E_{x2}}{R_{bm}} + \frac{0-E_{x2}}{R_{bo}} + i_{in} = 0 \quad (4)$$

where E_{x1} is the voltage of terminal 28, E_{x2} is the voltage of terminal 30, m and n are any positive integers other than zero, and i_{in} is assumed to be flowing in the direction indicated by the arrow in Fig. 1. The value of i_{in} is:

$$i_{in} = \frac{E_{x1}-E_{x2}}{R_f} \quad (5)$$

where, R_f is the resistance of control winding 20. Solving Equation 15, for E_{x1} yields:

$$E_{x1} = E_{x2} + R_f i_{in} \quad (6)$$

By rearranging Equations 3 and 4 the following equations are obtained:

$$\frac{E_{a1}}{R_{a1}} + \frac{E_{a2}}{R_{a2}} + \dots + \frac{E_{an}}{R_{an}} = i_{in} + \frac{E_{x1}}{R_{at}} \quad (7)$$

$$\frac{E_{x1}}{R_{ao}} + \frac{1}{R_{a1}} + \frac{1}{R_{a2}} + \dots + \frac{1}{R_{an}} = i_{in} + \frac{E_{x1}}{R_{at}}$$

and

$$\frac{E_{b1}}{R_{b1}} + \frac{E_{b2}}{R_{b2}} + \dots + \frac{E_{bm}}{R_{bm}} = -i_{in} + \frac{E_{x2}}{R_{bt}} \quad (8)$$

$$E_{x2} \left(\frac{1}{R_{bo}} + \frac{1}{R_{b1}} + \frac{1}{R_{b2}} + \dots + \frac{1}{R_{bm}} \right) = -i_{in} + \frac{E_{x2}}{R_{bt}}$$

where

$$\frac{1}{R_{at}} = \frac{1}{R_{ao}} + \frac{1}{R_{a1}} + \frac{1}{R_{a2}} + \dots + \frac{1}{R_{an}} \quad (9)$$

and

$$\frac{1}{R_{bt}} = \frac{1}{R_{bo}} + \frac{1}{R_{b1}} + \frac{1}{R_{b2}} + \dots + \frac{1}{R_{bm}} \quad (10)$$

Substituting the value of E_{x1} from Equation 6 in Equation 7, yields:

$$\frac{E_{a1}}{R_{a1}} + \frac{E_{a2}}{R_{a2}} + \dots + \frac{E_{an}}{R_{an}} = i_{in} + \frac{E_{x2} + i_{in} R_f}{R_{at}} \quad (11)$$

$$\frac{E_{x2} + i_{in} R_f}{R_{at}} = i_{in} \left(1 + \frac{R_f}{R_{at}} \right) + \frac{E_{x2}}{R_{at}}$$

Eliminating E_{x2} from Equations 11 and 8 yields:

$$\frac{R_{at}E_{a1}}{R_{a1}} + \frac{R_{at}E_{a2}}{R_{a2}} + \dots + \frac{R_{at}E_{an}}{R_{an}} - i_{in} \left(1 + \frac{R_f}{R_{at}} \right) R_{at} = \quad (12)$$

$$\frac{R_{bt}E_{b1}}{R_{b1}} + \frac{R_{bt}E_{b2}}{R_{b2}} + \dots + \frac{R_{bt}E_{bm}}{R_{bm}} + i_{in} R_{bt}$$

Also,

$$E_{b1} = p R_d i_{in} \quad (13)$$

or

$$i_{in} = \frac{E_{b1}}{p R_d} \quad (14)$$

where p is the open loop current gain of the amplifier. The relationship between R_d and R_{b1} is chosen to comply with:

$$R_d \leq \frac{R_{b1}}{10} \quad (15)$$

in order to insure that the gain of the amplifier is negligibly affected by E_{x2} .

From the foregoing it follows that:

$$\frac{R_{at}E_{a1}}{R_{a1}} + \frac{R_{at}E_{a2}}{R_{a2}} + \dots + \frac{R_{at}E_{an}}{R_{an}} = \frac{E_{b1}(R_{at} + R_{bt} + R_f)}{p R_d} + \frac{R_{bt}E_{b1}}{R_{b1}} + \frac{R_{bt}E_{b2}}{R_{b2}} + \dots + \frac{R_{bt}E_{bm}}{R_{bm}} \quad (16)$$

Since E_{b1} substantially equals the desired output voltage E_o , then

$$E_o \left[\frac{R_{at} + R_f}{p R_d} + R_{bt} \left(\frac{1}{p R_d} + \frac{1}{R_{b1}} \right) \right] = \frac{R_{at}E_{a1}}{R_{a1}} + \frac{R_{at}E_{a2}}{R_{a2}} + \dots + \frac{R_{at}E_{an}}{R_{an}} - \frac{R_{bt}E_{b2}}{R_{b2}} - \dots - \frac{R_{bt}E_{bm}}{R_{bm}} \quad (17)$$

If $p R_d$ is sufficiently large, so that:

$$\frac{p R_d R_{bt}}{R_{at} + R_f + R_{bt}} \gg R_{b1} \quad (18)$$

Equation 17 may be written as follows :

$$\frac{E_o R_{bt}}{R_{b1}} = \frac{R_{at}E_{a1}}{R_{a1}} + \frac{R_{at}E_{a2}}{R_{a2}} + \dots + \frac{R_{at}E_{an}}{R_{an}} - \frac{R_{bt}E_{b2}}{R_{b2}} - \dots - \frac{R_{bt}E_{bm}}{R_{bm}} \quad (19)$$

If the algebraic equation it is desired to solve is:

$$E_o K_{b1} = K_{a1} E_{a1} + K_{a2} E_{a2} + \dots + K_{an} E_{an} - K_{b2} E_{b2} - \dots - K_{bm} E_{bm} \quad (20)$$

where $K_{a1}, K_{a2} \dots K_{an}, K_{b1}, K_{b2} \dots K_{bm}$ are positive real numbers, it is necessary to evaluate the resistances $R_{ao}, R_{a1}, R_{a2} \dots R_{an}, R_{bo}, R_{b1}, R_{b2} \dots R_{bm}$ so that Equation 19 will give solutions for E_o identical to those obtained from Equation 20. For this to be true, then:

$$k_p = \frac{\frac{R_{at}}{R_{a1}}}{\frac{R_{at}}{K_{a1}}} = \frac{\frac{R_{at}}{R_{a2}}}{\frac{R_{at}}{K_{a2}}} = \dots = \frac{\frac{R_{at}}{R_{an}}}{\frac{R_{at}}{K_{an}}} = \frac{\frac{R_{bt}}{R_{b1}}}{\frac{R_{bt}}{K_{b1}}} = \frac{\frac{R_{bt}}{R_{b2}}}{\frac{R_{bt}}{K_{b2}}} = \dots = \frac{\frac{R_{bt}}{R_{bm}}}{\frac{R_{bt}}{K_{bm}}} \quad (21)$$

$$k_p = \frac{\frac{R_{at}}{R_{a1}} + \frac{R_{at}}{R_{a2}} + \dots + \frac{R_{at}}{R_{an}}}{\frac{R_{at}}{K_{a1}} + \frac{R_{at}}{K_{a2}} + \dots + \frac{R_{at}}{K_{an}}} = \frac{\frac{R_{bt}}{R_{b1}} + \frac{R_{bt}}{R_{b2}} + \dots + \frac{R_{bt}}{R_{bm}}}{\frac{R_{bt}}{K_{b1}} + \frac{R_{bt}}{K_{b2}} + \dots + \frac{R_{bt}}{K_{bm}}} \quad (22)$$

where k_p is a proportionality constant which will be evaluated later. Then from Equation 9 it follows that:

$$\frac{R_{at}}{R_{a1}} + \frac{R_{at}}{R_{a2}} + \dots + \frac{R_{at}}{R_{an}} = 1 - \frac{R_{at}}{R_{ao}} \quad (23)$$

and from Equation 10 it follows that:

$$\frac{R_{bt}}{R_{b1}} + \frac{R_{bt}}{R_{b2}} + \dots + \frac{R_{bt}}{R_{bm}} = 1 - \frac{R_{bt}}{R_{bo}} \quad (24)$$

Now let K_{at} be defined as:

$$K_{at} = K_{a1} + K_{a2} + \dots + K_{an} \quad (25)$$

and K_{bt} be defined as:

$$K_{bt} = K_{b1} + K_{b2} + \dots + K_{bm} \quad (26)$$

Substituting Equations 23, 24, 25 and 26 in Equation 22 yields:

$$k_p = \frac{1 - \frac{R_{at}}{R_{ao}}}{K_{at}} = \frac{1 - \frac{R_{bt}}{R_{bo}}}{k_{bt}} \quad (27)$$

In order to obtain realizable values for the resistances R_{ao} and R_{bo} the proportionality constant k_p is assigned the values of

$$k_p = \frac{1}{K_{bt}} \text{ or } k_p = \frac{1}{K_{at}} \quad (28)$$

whichever is the smaller. If

$$\frac{1}{K_{bt}} \text{ is less than } \frac{1}{K_{at}}$$

then:

$$R_{ao} = \frac{R_{at}K_{bt}}{K_{bt} - K_{at}}, \text{ and } R_{bo} = \infty \quad (29)$$

the value for any resistor R_{ai} is given by:

$$R_{ai} = \frac{R_{at}K_{bt}}{K_{at}} \quad (30)$$

and the value for any resistor R_{bi} is given by:

$$R_{bi} = \frac{R_{bt}K_{bt}}{K_{bt}} \quad (31)$$

If

$$\frac{1}{K_{at}} \text{ is less than } \frac{1}{K_{bt}}$$

then:

$$R_{bo} = \frac{R_{bt}K_{at}}{K_{at} - K_{bt}}, \text{ and } R_{ao} = \infty \quad (32)$$

the value for any resistor R_{ai} is:

$$R_{ai} = \frac{R_{bt}K_{at}}{K_{at}} \quad (33)$$

and the value for any resistor R_{bi} is:

$$R_{bi} = \frac{R_{bt}K_{at}}{K_{bt}} \quad (34)$$

The values for each of the coefficients K_{a1} , K_{a2} . . . K_{an} and K_{b1} , K_{b2} . . . K_{bm} are given, and the value of p is known as is the value of R_d . Values for R_a , R_{at} and R_{bt} may be chosen to fulfill the basic assumption that

$$\frac{pR_dR_{bt}}{R_{at} + R_{bt} + R_{bi}}$$

is on the order of 100 or more times greater than R_{bi} and that R_{bi} is equal to, or greater than $10 R_d$. Knowing these values it is possible to work out from Equations 29, 30, 31, 32, 33 and 34 the necessary values of each of the resistors, R_{a1} , R_{a2} . . . R_{an} , R_{a1} and R_{b1} , R_{b2} . . . R_{bm} , R_{bo} to solve the Equation 20 by analogy. It should be noted that if K_{at} equals K_{bt} then resistors R_{bo} and R_{ao} are both infinite, or they are omitted from the circuit.

There is no limit as to polarity or magnitude of the input voltages E_{a1} , E_{a2} . . . E_{an} , E_{b1} . . . E_{bm} except that for accurate results E_{b1} , or E_o , must remain positive and within the limits over which E_o is a linear function of i_{in} .

In order to solve an equation of the form

$$E_{b1} = E_{a1} + E_{a2} + E_{a3} - E_{b2} - E_{b3} \quad (35)$$

the modification illustrated in Fig. 2 is used. The values of the coefficients K_{a1} , K_{a2} , K_{a3} and K_{b1} , K_{b2} , K_{b3} are each equal to 1 so that K_{at} equals 3 and K_{bt} equals 3. Assuming a value of R_{at} equals R' and R_{bt} equals R' it follows that the value of resistors R_{a1} , R_{a2} , R_{a3} are:

$$R_{a1} = R' \times 3 \times \frac{1}{1} = 3R' \quad (36)$$

$$R_{a2} = R' \times 3 \times \frac{1}{1} = 3R' \quad (37)$$

and

$$R_{a3} = R' \times 3 \times \frac{1}{1} = 3R' \quad (38)$$

Similarly it can be shown that the values of each of the resistors R_{b1} , R_{b2} and R_{b3} are also equal to $3R'$, or all the resistors of the input networks 24 and 26 are equal to each other. Since $K_{at} = K_{bt}$ there is no necessity for a grounded resistor corresponding to resistor R_{ao} and R_{bo} of Fig. 1. It is, of course, necessary that the conditions of Equations 15 and 18 be complied with.

By modifying the circuit of Fig. 2 to that of Fig. 3, an effective isolation amplifier, one having a high input impedance and a low output impedance, is obtained.

15 Since the input impedance, Z_{in} is defined as follows:

$$Z_{in} = \frac{E_{b1}}{i_{in}} \quad (39)$$

and since the magnitude of the current i_{in} in control winding 20 is determined by

$$i_{in} = \frac{E_{a1}}{pR_d} \quad (40)$$

it follows that:

$$Z_{in} = \frac{pR_d E_{a1}}{E_{b1}} \quad (41)$$

Since the relation between E_{a1} and E_{b1} is defined by:

$$E_{a1} \equiv E_{b1} \quad (42)$$

30 it follows that:

$$Z_{in} = pR_d \quad (43)$$

Since the open loop current gain, p of an amplifier of the type illustrated is on the order of 6000 and the reasonable value for R_d is 1000 ohms, an input impedance Z_{in} of 6 megohms can be easily obtained.

Obviously many modifications and variations of the present invention are possible in the light of the above teachings. It is, therefore, to be understood that within the scope of the appended claims the invention may be practiced otherwise than as specifically described.

What is claimed is:

1. A magnetic summing amplifier comprising a conventional voltage doubling magnetic amplifier having two magnetic cores adapted to produce an output voltage and an output current, a positive feedback winding through which the output current of said magnetic amplifier flows, a bias winding, a control winding having two control terminals, a first input circuit having "n" input terminals and "n" input resistors, each input resistor having two terminals, one terminal of each input resistor of the first input circuit being connected to one of the control terminals of said control winding, the second terminal of each input resistor being connected respectively to an input terminal of the first input circuit, a second input circuit having "m" input terminals and "m" input resistors, each input resistor having two terminals, one terminal of each input resistor of the second input circuit being connected to the other control terminal of said control winding, the second terminal of each input resistor of the second network being connected respectively to an input terminal of the second input circuit, "m" and "n" being integers other than zero, and substantially D. C. voltages adapted to be applied to the input terminals of the terminals of the two input circuits, the magnitude of one of the substantially D. C. voltages applied to one of the resistors of the second network being substantially equal to the output voltage, whereby the output voltage of said magnetic amplifier equals the sum of the voltages applied across the first network of said resistor, less the voltage applied across said second network with the exception of the voltage which is substantially equal to the output voltage which is applied to said second network.

2. An electrical device as defined in claim 1 in which

the resistance of each resistor in said first and second input circuits is substantially equal.

3. An electrical device as defined in claim 1 in which "m" equals "n."
4. An electrical device as defined in claim 1 in which "m" and "n" equal three.
5. An electrical device as defined in claim 1 in which "m" and "n" equal one.
6. A summing magnetic amplifier for solving by analogy an equation of the form:

$$K_{b1}E_{b1} = K_{a1}E_{a1} + K_{a2}E_{a2} + \dots$$

$$K_{a1}E_{a1} - K_{b2}E_{b2} - \dots - K_{bm}E_{bm}$$

where K_{a1} , K_{a2} . . . K_{an} and K_{b1} , K_{b2} . . . K_{bm} are each positive real numbers, E_{a1} , E_{a2} . . . E_{an} , E_{b1} , E_{b2} . . . E_{bm} are variables represented by substantially D. C. voltages, and "m" and "n" are positive integers other than 0, comprising a high gain magnetic amplifier having a control winding having first and second control terminals at the ends thereof, a positive feedback winding, a load resistor, a circuit means for causing substantially all the output current of said amplifier to flow through said feedback winding and said load resistor, a first and a second input circuit, said first input circuit having "n" input terminals and "n" input resistors of predetermined values, said input resistors being connected between an input terminal and the first control terminal of the control winding, said second input circuit having "m" input terminals and "m" input resistors of predetermined value, each of said input resistors of said second input circuit being connected between an input terminal of said second circuit and the second control terminal of control winding, input voltages E_{a1} , E_{a2} . . . E_{an} being connected respectively to the input terminals of the first circuit and input voltages E_{b1} , E_{b2} . . . E_{bm} being connected respectively to the input terminals of the second circuit, input voltage E_{b1} being the voltage across the load resistor due to the output current flowing therethrough, means for connecting a first balancing resistor of predetermined value between said first control terminal and ground if K_{bt} is greater than K_{at} , and means for connecting a second balancing resistor of predeter-

mined value connected between the second control terminal and ground if K_{at} is greater than K_{bt} , said balancing resistors being omitted if K_{bt} equals K_{at} where:

$$K_{at} = K_{a1} + K_{a2} + \dots + K_{an}$$

and

$$K_{bt} = K_{b1} + K_{b2} + \dots + K_{bm}$$

7. A magnetic summing amplifier comprising a conventional voltage doubling magnetic amplifier having two magnetic cores adapted to produce an output voltage and an output current, a positive feedback winding through which the output current of said magnetic amplifier flows, a bias winding, and a control winding, each of said windings being around both of said cores, a first input circuit of parallel connected input resistors, each input resistor having one terminal connected to one terminal of said control winding, the other terminals of each of said input resistors of said first network adapted to be connected respectively to sources of substantially D. C. potential, a second network of parallel connected input resistors, one terminal of each of said input resistors in said second network connected to the second terminal of said control winding, the other terminal of each of said resistors in said second network adapted to be connected respectively to sources of substantially D. C. potential, the number of resistors in said first and second networks and the resistance of each resistor of said first and second network being substantially equal, the magnitude of one of the substantially D. C. voltages applied to one of the resistors of said second network being substantially equal to the output voltage, whereby the output voltage of said magnetic amplifier equals the sum of the voltages applied across the first network of said resistor, less the voltages applied across said second network with the exception of the voltage which is substantially equal to the output voltage which is applied to said second network.
